UNITED STATES PATENT OFFICE.

WILLIAM J. CRAIG, OF NEWTONVILLE, ASSIGNOR OF ONE-HALF HIS RIGHT
TO JOSEPH SOUTHWICK AND GEORGE W. PIERCE, OF BOSTON, MASS.

IMPROVEMENT IN DOMINO-BOXES.

Specification forming part of Letters Patent No. **155,792**, dated October 13, 1874; application filed
September 4, 1874.

To all whom it may concern:

Be it known that I, WILLIAM J. CRAIG, of Newtonville, Massachusetts, have invented a Domino-Box, of which the following is a specification:

Figure 1 represents the box in perspective, bottom upward. A, the bottom, is made of slate, or other material suitable to write upon, and set in a short distance, so as not to be flush with the edge B. This edge B forms a rim extending all around the slate A, to keep a pencil from rolling off if left upon the slate when the box is placed bottom upward. The rim B also serves as a guard to save the slate from contact with other objects when the box is accidentally dropped, thus tending to prevent its being broken.

Fig. 2 is an elevation of the box-cover, with the under side toward the eye. D and E are holes for two pencils, bored in the thickness of the cover to a suitable depth from the left-hand end.

The pencil, Fig. 3, is shown in position in the hole D, Fig. 2, by dotted lines. Each pencil is headed with a bit of brass or wire, or other suitable contrivance for the purpose, to be immediately explained.

K and L, Fig. 2, are notches in the lid C, at the mouths of the holes or tubes D and E. G, Fig. 3, is a bit of wire twisted about the

head of the pencil F in a groove made for the purpose, and having a projecting point. This point, catching in the notch K, prevents the pencil from slipping too far into the hole D made to receive it, and at the same time facilitates the removal of the pencil by the fingernail when wanted for use.

Fig. 4 is a section of the lid, Fig. 2, through the line I J, showing the openings of the holes D and E.

The device, contrived for a domino-box, is equally applicable to many other games.

I claim—

1. A domino or other box for game apparatus, having its bottom A of slate or other similar material for tallying purposes, substantially as set forth.
2. A domino or other box for game apparatus, provided with the slate bottom, and the cover having the pencil-receptacle therein, substantially as described and shown.
3. In a box, constructed substantially as herein described, the cover provided with the receptacles D E and notches K L, substantially as described, and for the purpose set forth.

WILLIAM J. CRAIG.
